(No Model.)

B. BOYER.
CAR BRAKE.

No. 400,542.

Patented Apr. 2, 1889.

J. P. Coleman.

INVENTOR.

Baasler Boyer
by A. G. Neymann
Attorney.

UNITED STATES PATENT OFFICE.

BASSLER BOYER, OF LEBANON, PENNSYLVANIA.

CAR-BRAKE.

SPECIFICATION forming part of Letters Patent No. 400,542, dated April 2, 1889.

Application filed February 2, 1889. Serial No. 298,496. (No model.)

To all whom it may concern:

Be it known that I, BASSLER BOYER, a citizen of the United States of America, residing at Lebanon, in the county of Lebanon and State of Pennsylvania, have invented certain new and useful Improvements in Car-Brakes, of which the following is a specification.

My invention has relation to improvements in car-brakes; and the object is to improve the mechanism of that certain invention in car-brakes (shown and described in Letters Patent No. 394,452, dated December 11, 1888, granted to me) by adapting the constructions and arrangement of the parts to any number of wheels over a single pair, as will be hereinafter specified. This I accomplish by the mechanical devices illustrated in the accompanying drawings, wherein—

Figure 1 is a bottom plan view of a car-body and trucks having my improvements connected thereto. Fig. 2 is a sectional view taken through the timbers of the truck and a side view of the operating mechanism of the brake.

25 In the drawings, A designates the bottom of the car, provided with bottom timbers, 1, and a central cross-timber, 2, to which the system of operating-levers are fulcrumed.

B denotes the truck on which the car-body 30 is supported by means of bearing-boxes, as usual.

C denotes the cross-timbers, fixed to the bottom of the car centrally between the wheels of the trucks, the links or rods sustaining the 35 brake-bars being connected to these cross-timbers, substantially as shown. Below the cross-timber C is arranged a cross-piece, D, a space being left between these two timbers for the purpose of affording room within which 40 to dispose the disks.

E designates the brake-bars, suspended by links or rods 3 from the cross-timbers C. These brake-bars are provided with brake-shoes 4, as usual. In the middle rear part of 45 the brake-bars are bearing-blocks 5, having their inner edge faces concaved to conform substantially to the sweep of the elliptical disks, substantially as shown in the drawings.

F designates the elliptical disks, made of 50 any suitable material, having strength sufficiently to withstand the intended uses. These elliptical disks are mounted on vertical shafts

6, having bearings in the cross-timbers, or they may be arranged in hangers on the upper timbers. The elliptical disks are made 55 of such width in transverse section as that when arranged with their longitudinal center in the direction of the cross-timbers the brake-bars will be free to swing inward and leave the brake-shoes free from the wheels. 60

To restrain the too rapid turning of the disks in applying the brakes and to return the disks to a position of "off-brake" when the power has been disconnected or released, springs 7 are connected to the respective disks, 65 the force of which restrains the rotation and bear to throw the disks in reverse movement to that extended by the power.

As shown and described in my former Letters Patent cited, the foregoing brake mechanism can be operated by either a hand-brake staff or by the steam air-brake appliances, or both in conjunction. The hand-brake leverage is designated by a rod, 8, connected to one end of the disk, the other end being connected to a lever, 9, mounted on a bearing and having the upper end connected to a rod, 10, connected to one end of a lever, 11, fulcrumed on the bottom of the car. At the other end of the lever 11 is connected a brake-rod, 12, connected to the brake-staff on the platform of the car. I have not shown this last connection, as it is so well known as not to require special description or illustration. The piston 13 of the steam or air brake apparatus 14 is connected to the lever 11, to which is connected one end of a rod, 15, connected at the other end to the disks, substantially as shown in Fig. 1 of the drawings, the lever connections and movements in this relation 85 being shown in dotted lines. The interposition of the vertically-arranged lever 9 is intended to provide connection to the disks which will turn them on a horizontal plane and avoid torsional strains; but in a connection involving a direct attachment to the disks 90 these levers may be dispensed with.

The foregoing description involves the mechanism requisite to the application of my improved brake to the one side of the wheels 100 of a truck or trucks, and is substantially that shown and described in my cited Letters Patent.

It is the object, as heretofore mentioned, of

my present invention and improvements to adapt the foregoing operating mechanism to brake-bars clamping or braking the wheels of the truck on both sides, as shown in Fig. 2 of the drawings. Specifically describing my improvements, 16, 17 denote brake-bars suspended from the timbers of the car by links or chains 18 and arranged opposite to the inner brake-bars, as shown. These additional 10 brake-bars are provided with the usual brake-shoes, 4, and are so hung from the car or supports as to swing free from the wheels when off brakes. On each of the inner brake-bars, being those arranged between the wheels, is 15 connected a bar, 20, having the other ends connected to the opposite outer brake-bar, as shown. This arrangement and connection, it will be perceived, eventuate in simultaneously moving all the brake-bars toward the 20 face of the wheels and upon opposite sides thereof by the turning of the disks, and that all are released when the disks are turned off-brakes. The connections, as shown in the drawings, may be either direct or through the 25 interposition of a lever, 21, having a connecting-rod leading to the brake-bar.

Having thus described the mechanism involved, I now proceed to particularly point

out and distinctly claim the improvements and combinations which I claim as my invention, to wit:

1. The combination of the pivotally-supported rotary elliptical disks, the inner suspended brake-bars arranged between the wheels of the truck, a lever to rotate the disks on their axis, the outer suspended brake-bars arranged to brake against the outer faces of the wheels of the trucks, and connecting-rods from the inner brake-bars to the opposite outer brake-bar, substantially as described.

2. The combination, with the rotatable elliptical disk, and means, substantially as described, for turning it on its axis, of inner and outer brake-bars arranged to brake on both sides of the wheels, and rods connecting the inner and outer brake-bars, whereby all the brake-bars move synchronously on and off brakes, substantially as described.

In witness whereof I have hereunto set my hand in the presence of two attesting witnesses.

BASSLER BOYER.

Attest:

S. G. HORST,

PETER HAUER.
